HUB CAP

Delmer Peterkin, 627 Wentworth Ave.,
Santa Barbara, Calif.

Filed Apr. 5, 1960, Ser. No. 60,057

Term of patent 14 years

(Cl. D14—30)

FIG. 1

Fig. 1 is a front elevational view of a hub cap showing my new design;

Fig. 2 is a top plan view thereof; and

Fig. 3 is a profile view taken on the line 3—3 of Fig. 1, showing the outer contour of the hub cap.

The tire and rim shown in broken lines in Figs. 1 and 3 are included for illustrative purposes only.

I claim:

The ornamental design for a hub cap, as shown and described.
